IGNITER FOR COAL FURNACES

Alfred Shearman, Toronto, Ontario, Canada

Application February 8, 1933. Serial No. 655,705

2 Claims. (Cl. 175—115)

The invention appertains in particular to a furnace equipped with a coal blower.

The aim of the invention is to produce an efficient and reliable igniter for preventing explosions or what is commonly referred to as "blow-backs" in the furnace due to accumulated gases suddenly becoming ignited.

The invention attains its object by the provision of an electric system for producing an arc over and above the coal bed to ignite gases rising therefrom and in the adoption of an element designed to act in conjunction with the arc to catch gases to ensure their combustion.

The device comprises in the main an inverted chambered element in which gases are caught and their combustion assured by an arc from electrodes surrounded by a support extending through the wall of the charging door of the furnace.

10 A guard is preferably employed to protect the electrode points against injury, while the aforesaid support by loosely surrounding the electrodes provides an air space that heat insulates them.

15 Referring to the accompanying drawing, Figure 1 is a vertical sectional view of the device applied to a furnace.

Figure 2 is a plan view of the underside of the device showing it partly in section.

20 Figure 3 is a cross section taken on the line 3—3 of Figure 2.

Figure 4 is a further cross section but taken on the line 4—4 of Figure 2.

25 Like numerals of reference indicate corresponding parts in each of the figures throughout the drawing of the invention.

In the drawing in which the preferred construction is illustrated, the usual feed or charging door of the furnace is denoted at 5 and the fire bed is represented at 6. It is desirable to mount the device upon the feed door in order that it may swing clear of the combustion chamber when replenishing the coal. To this end the door is provided with an opening through which the support or casing 7 projects into the combustion chamber.

30 The inner end 8 of the support carries a head 9 in the form of an inverted cup-shaped member adapted to catch gases rising from the fire bed 7. The vertical wall 9' has horizontal openings through which electrodes 10 and 11 are inserted. The points 13 are bent towards each other and are spaced to provide a gap for producing the arc. The points are disposed well within the head which composes a canopy for them.

35 To shield the points against injury the canopy may have a guard consisting of straps as at 14 extending from one side to the other of the head and preferably constructed integrally therewith. The head may be of a cast iron member detachably secured to the sup-

port by fastening elements. This is achieved by bolts and nuts 15 securing the lugs 16.

The electrodes are held in place by the provision of shoulders in the porcelains 17 which are engaged by threaded bushings 18. The electrodes are of a length sufficient to extend through and beyond the outer end of the casing so that the terminals 19 may be attached to the leads from the electric circuit. These parts may be housed by the cover 20 of the transformer, not shown since it does not form a part of the present invention.

40 It is preferred to bolt the support to the door. To this end lugs 21 are furnished on the sides of the support to take the bolts 22. Spacers 23 of different lengths may be used to vary the distance at which the head is located in the combustion chamber.

45 It will be manifest that according to this invention unconsumed gases rising from the fire bed are caught in the canopy 9 and ignited by the arc between the electrodes and in this manner effectively prevent explosions of accumulated gases. The electrodes for almost their entire length are heat insulated by the air space within the casing, which communicates with the outside of the furnace. The arcing of course need only take place while the blower is operating.

50 Whilst the invention is shown and described in what is deemed its most practical form, various changes may be resorted to without departing from the spirit and scope of the appended claims.

55 What I claim is:—

1. In a device of the class described, a head for disposition in the combustion chamber of a furnace, electrodes projecting into the head and having spaced points for producing an arc, said head forming a canopy for the electrodes and being adapted to catch gases, a guard for the underside of the canopy, and a support for the head.

60 2. In a device of the class described, a head for disposition in the combustion chamber of a furnace, electrodes projecting into the head and having spaced points for producing an arc, said head forming a canopy for the electrodes and being adapted to catch gases, straps extending across the underside of the canopy to form a guard for the electrodes, and a support for the head.

65 ALFRED SHEARMAN.
